CLAIM

The ornamental design for a pump, as shown and described.

DESCRIPTION

FIG. 1 is a top, front and left side perspective view of a pump, showing our new design;

FIG. 2 is a front view thereof;

FIG. 3 is an enlarged view of the features shown in circle 3 from FIG. 2 in a perspective view;

FIG. 4 is a left side view thereof;

FIG. 5 is a rear view thereof;

FIG. 6 is a right side view thereof;

FIG. 7 is an enlarged view of the features shown in circle 7 of FIG. 6 in a perspective view;

FIG. 8 is a top view thereof; and,

FIG. 9 is a bottom view thereof.

The long-dash, short-dash lines in the drawings define the bounds of the claimed design and form no part thereof. The dash-dash broken lines in the drawings depict portions of the pump that form no part of the claimed design.
